(57) **CLAIM**

The ornamental design for a mobile kiosk service robot as shown and described.

DESCRIPTION

FIG. 1 is an isometric view of a mobile kiosk service robot.

FIG. 2 is a bottom isometric view thereof.

FIG. 3 is another isometric view thereof.

FIG. 4 is a front view thereof.

FIG. 5 is a rear view thereof.

FIG. 6 is a left side view thereof.

FIG. 7 is a right side view thereof.

FIG. 8 is a top view thereof; and,

FIG. 9 is a bottom view thereof.

Claimed portions of the kiosk service robot may also be line-shaded. Diagonal line shading, as seen in the rectangular areas in the upper half of the mobile kiosk service robot, indicates surfaces that have transparency.
